UNITED STATES PATENT OFFICE

2,423,934

AGITATOR AND DISPENSER FOR
LUBRICATING COMPOUNDSHans L. C. Hansen, Detroit, Mich., assignor to
Chicago Rawhide Manufacturing Company,
Chicago, Ill., a corporation of Illinois

Application July 28, 1943, Serial No. 496,451

4 Claims. (Cl. 222—246)

1

The object of this invention is to provide an automatic lubricator of new and improved construction for use in applying oil, drawing compounds, or other fluid or semi-fluid material to stock being formed or cut in a press or other machine, or in feeding such material into processing or forming dies or molds in a machine, which lubricator is adapted to be attached to and intermittently actuated by the machine to dispense the lubricant or other material in unit quantities of any desired amount irrespective of the amplitude of movement of the particular part of the machine acting upon the same.

While the foregoing statement is indicative of the nature of the invention, other more specific objects and advantages will be apparent to those skilled in the art upon a full understanding of the construction of the new mechanism.

A preferred embodiment of the invention is presented herein by way of exemplification, but it will of course be appreciated that the invention is susceptible of incorporation in other structurally modified forms coming equally within the scope of the appended claims.

In the accompanying drawing:

Fig. 1 is a vertical section through the center of an automatic dispensing mechanism constructed in accordance with the invention, taken on the line 1—1 of Fig. 3, showing the mechanism in its non-feeding position;

Fig. 2 is a similar section, showing the mechanism in its feeding position; and

Fig. 3 is a plan view of the mechanism.

The mechanism shown in the drawing consists of a reservoir 10 which is adapted to contain a substantial supply of the lubricant or other material to be fed. The reservoir is provided in its bottom with an outlet 11, and the outlet is connected to a flexible conduit 12 which is adapted to extend to the part of the associated machine (not shown) where the lubricant is to be used. The reservoir is provided at one of its sides with a bracket 13 which is adapted to be attached to the machine.

The outlet 11 from the reservoir contains a conical valve seat 14 which is normally closed by a conical valve 15 on the lower end of a vertically reciprocable rod 16. The rod 16 is provided, beneath the valve 15, with a longitudinally slotted pilot portion 17 which slidably fits within the outlet 11 and serves to maintain the valve centered with respect to the seat. The rod 16 is positioned within a tube 18, which tube is vertically reciprocable with respect to both the rod 16 and the reservoir 10. The tube 18 is provided at its

2

lower end with a bushing 19 which slidably fits about the rod 16. The upper end of the tube 18 is bifurcated at 20 and slidably embraces a bar 21 which is arranged crosswise of the top of the reservoir and is secured by screws 22 or other means to the sides of the latter.

The bar 21 carries a set screw 23 which extends downwardly from the bar through the center of the tube 18 to a point closely adjacent but normally spaced from the upper end of the rod 16. The lower end of the screw 23 constitutes an adjustably positioned stop which determines the extent to which the rod 16 will move upwardly upon each stroke of the machine and consequently the extent to which the valve 15 will be lifted from its seat on each stroke.

The upper end of the rod 16 is provided with an enlarged head 24 which slidably fits within the tube 18. A coil spring 25 encompasses the rod 16 between the head 24 and the upper end of the bushing 19 in the tube 18. The spring 25 acts between the tube and the rod to raise the latter each time the tube is raised, but the spring is of such length as to exert no upward pressure on the rod when the tube is in its lowered position. A second coil spring 26 encompasses the screw 23 and is compressed axially between the lower edge of the bar 21 and the head 24 on the upper end of the rod 16. The spring 26 exerts enough pressure on the head 24 to re-seat the valve 15 and keep the same seated when the tube 18 is in its lowered position. The spring 25 is made to take a greater load than the spring 26, with the result that when the tube 18 is raised the spring 25 will further compress the spring 26 and will lift the rod 16 and consequently the valve 15 until the upward movement of the rod 16 is stopped by engagement of the head 24 with the lower end of the screw 23.

40 The tube 18 is adapted to be raised intermittently by the movement of some part of the associated machine—for example, the ram on a press—through the intermediary of a lever 27 which is pivoted intermediate its ends at 28 to the upper end of the attaching bracket 13. The inner end of the lever 27 is bifurcated to loosely embrace the upper bifurcated end of the tube 18 and is pivotally connected to the latter by pins 29 in the sides of the tube which slidably fit within elongated slots 30 in the bifurcated portion of the lever. The outer end of the lever 27 is provided with an impact portion 31 which is adapted to be arranged in the path of movement of the ram or other actuating part.

55 Where the mechanism is to be used with draw-

ing compounds or other mixtures the tube 18 may advantageously be provided with an agitator 32 for use in keeping the ingredients in a state of suspension while the mixture is being dispensed. The agitator 32 may consist of a disk 33 of slightly less diameter than the reservoir 10, which disk may be attached to the lower end of the tube 18 within the reservoir and be provided with stirring formations such as an upturned rim 34 and openings 35 equipped with circularly directing tongues 36 above such openings.

By adjusting the position of the screw 23 in the arm 21 the extent to which the valve 15 will be lifted from its seat 14 upon each oscillation of the lever 27 can be adjusted within close limits irrespective of the amplitude of movement of the ram or other part. After the screw 23 has been adjusted it can be secured in its adjusted position by tightening a lock nut 37 on the screw against the upper edge of the bar 21. The screw 23 can be turned all of the way down against the head 24 of the rod 16—in which event the mechanism will not feed any lubricant at all, or the screw 23 can be backed up to a point where the rod 16 will move practically as a unit with the tube 18 throughout the full stroke of the latter, thus enabling any desired unit quantity of the lubricant to be dispensed upon each stroke of the mechanism. The rate of feed of the mechanism can be regulated in this way with great exactness, even while the mechanism is in operation.

I claim:

1. A mechanism for attachment to a press or other machine for intermittently dispensing unit quantities of a fluid or semi-fluid material in conjunction with the operation of the machine, comprising a reservoir which is provided in its bottom with an outlet, a valve seat in the outlet, a vertically reciprocable rod provided adjacent its lower end with a valve which in its lowered position normally engages the seat to close the outlet, a vertically reciprocable tube slidably encompassing and in guiding relation to the rod, a lever operatively connected with the tube, which lever is adapted to be oscillated by a movable part of the associated machine to intermittently raise the tube, a spring acting between the tube and the rod to raise the rod each time the tube is raised, an adjustable stop in the path of movement of the rod for limiting the extent to which the rod is raised by the tube irrespective of the extent to which the tube is raised by the lever, and a second spring acting against the rod in opposition to the first spring to lower the rod when the tube is lowered.

2. A mechanism for attachment to a press or other machine for intermittently dispensing unit quantities of a fluid or semi-fluid material in conjunction with the operation of the machine, comprising a reservoir which is provided in its bottom with an outlet, a valve seat in the outlet, a vertically reciprocable rod provided adjacent its lower end with a valve which in its lowered position normally engages the seat to close the outlet, a vertically reciprocable tube slidably encompassing the rod, a lever connected with the tube, which lever is adapted to be oscillated by a movable part of the associated machine to intermittently raise the tube, a spring acting between the tube

and the rod to raise the rod each time the tube is raised, an adjustable stop in the path of movement of the rod for limiting the extent to which the rod is raised by the tube irrespective of the extent to which the tube is raised by the lever, a second spring acting against the rod in opposition to the first spring to lower the rod when the tube is lowered, and an agitator in the reservoir connected with the tube for stirring up the material in the reservoir each time the tube is raised.

5 3. A mechanism for attachment to a press or other machine for intermittently dispensing unit quantities of a fluid or semi-fluid material in conjunction with the operation of the machine, comprising a reservoir which is provided with an outlet, a valve seat in the outlet, a reciprocable rod provided in the reservoir with a valve which in its advanced position normally engages the seat to close the outlet, a reciprocable member in the reservoir alongside the rod in guiding relation thereto, a lever operatively connected with the member, which lever is adapted to be oscillated by a movable part of the associated machine to intermittently reciprocate the member, a spring acting between the member and the rod to retract the rod each time the member is reciprocated, an adjustable stop in the path of movement of the rod for limiting the extent to which the rod is retracted by the member irrespective of the extent to which the member is retracted by the lever, and a second spring acting against the rod in opposition to the first spring to advance the rod when the member is advanced.

10 4. A mechanism for intermittently dispensing unit quantities of a fluid or semi-fluid material, comprising a reservoir for said material which is provided with an outlet, a valve seat in the outlet, a reciprocable rod in the reservoir with a valve which in its advanced position normally engages the seat to close the outlet, a reciprocable member in the reservoir alongside the rod in guiding relation thereto, means to reciprocate the member, a spring acting between the member and the rod to retract the rod each time the member is reciprocated, an adjustable stop in the path of movement of the rod for limiting the extent to which the rod is retracted by the member irrespective of the extent to which the member is retracted by the lever, and a second spring acting against the rod in opposition to the first spring to advance the rod when the member is advanced.

Certificate of Correction

Patent No. 2,423,934.

July 15, 1947.

HANS L. C. HANSEN

It is hereby certified that error appears in the printed specification of the above numbered patent requiring correction as follows: Column 4, line 38, claim 4, after "reservoir" insert *provided*; and that the said Letters Patent should be read with this correction therein that the same may conform to the record of the case in the Patent Office.

Signed and sealed this 2d day of December, A. D. 1947.
